PUMP AND DISTRIBUTOR MECHANISM

Andrew A. Kucher, Grosse Pointe Farms, Mich.,
assignor to Bendix Aviation Corporation, De-
troit, Mich., a corporation of Delaware

Application May 28, 1943, Serial No. 488,865

7 Claims. (Cl. 103—131)

1

This invention relates to pump and distributor mechanisms, and, while useful for various purposes, it is herein described as embodied in a mechanism for feeding fuel to a multi-cylinder internal combustion engine.

An object of the invention is to provide a compact and light-weight mechanism of this character, capable of being readily manufactured with high precision.

Another object is to provide a pump, having multiple outlets, with a simple adjustment for quickly and accurately varying the delivery thereof and operative to adjust the delivery of all its outlets in exactly the same amount.

A further object is to provide such an adjustment having means by which it can be actuated while the pump is running.

These and other objects of the invention, and various novel constructions and arrangements embodied in the mechanism, will be apparent from the following description of the illustrative mechanism shown in the accompanying drawing, in which:

Figure 1 is an elevation of a pump and distributor embodying my invention, partly broken away in central section;

Figure 2 is a section on line 2—2 of Figure 1;

Figure 3 is a partial elevation of one of the valve assemblies;

Figure 4 is a partial section on the line 4—4 of Figure 3;

Figure 5 is an exploded perspective of the end of the driving shaft, and an adjustment member associated therewith;

Figure 6 is a section of an adjustable eccentric carried by the driving shaft, and of a sleeve which is actuated by the parts shown in Figure 5 to adjust the effective throw of the eccentric.

The particular embodiment of the invention illustrated is intended for feeding fuel to an internal combustion engine or a Diesel cycle injection engine. It comprises a case, shown made in sections including a cylinder 10 and two plates 12 and 14 having respectively series of inlet openings 16 and outlet openings 18. The plates constitute the side walls of the pumping chambers described below.

A plate 20, has openings 22 leading into inlet valve recesses 24 (in the side plate 12), is associated with the side plate 12. Similar recesses 26 for the outlet valves are in an end plate 28, and each of these outlet valve recesses communicates with an outlet opening 18 and with one of a plurality of conduit connections 30 leading to one of the engine cylinders. The end plate

2

28 has lugs 32 having openings for bolts or the like for mounting the whole assembled unit.

At the inlet side there is arranged an end plate 34 formed with an annular space or manifold 36 which receives fuel from an intake connection 38, and leads it to all of the inlet openings 22. The above-described parts are secured together in one compact unit by means such as bolts 40.

10 The two valve assemblies are just alike, the inlet valve assembly being arranged between plates 12 and 20, and controlling the passage of fuel through the inlet passages 22 (and therefore through inlet openings 16), while the outlet valve assembly is arranged between plates 14 and 28 and controls the passage of fuel through the outlet openings 18 to the connections 30.

Each valve assembly comprises a carrier plate 42, annular in shape and located by a pin 44 carried by the plate 20 or 14. The carrier plate 42 is formed with recesses receiving the enlarged inner ends of valve flappers 46 and corresponding valve springs 48. It will be noted that raised valve seats are formed around the openings 22 and 18, for engagement by the corresponding valve flappers 46.

The end plate 28 is provided at its center with a bearing 50 for a driving shaft 52, and with an oiler 54 and a seal 56. On the end of the shaft 52 is formed an eccentric 58, and projecting axially from the end of the shaft is a square key 60 received in a corresponding opening in an adjustment-operating member 62. Member 62 has a lug 64 received in a cam slot 66 formed in a rotatable sleeve 68 journaled in the end plate 34 and provided with a stuffing box 70.

The sleeve 68 carries a pin 72 seating in a recess in an eccentric 74 mounted on the eccentric 58. Eccentrics 58 and 74 are of the same width 40 as cylinder 10, and turn in the plane of the cylinder. Member 62 is actuated, against the resistance of a spring 76, by pushing on a thrust part 78 backed up by a thrust bearing 80. Pushing on the thrust part 78 actuates the lug 64 in the cam slot 66 to turn the eccentric 74 upon the eccentric 58. In one extreme position the one eccentric offsets the other, and the outer surface of eccentric 74 is coaxial with respect to shaft 52; in this position there is no pumping action. By shifting the member 62 from this extreme position, the effective throw of the eccentric 74 is gradually increased.

Encircling the eccentric 74, and driven by it, is a central flange 82 of a cylindrical member 84 which moves within the cylinder 10 between the

plates 12 and 14, with as little side clearance as possible. The cylindrical member 84 is formed with radial slots slidably receiving vanes 86, the outer ends of which are formed for line contact with the inner face of the cylinder 10.

The inner ends of the vanes 86 seat against a ring 88 arranged in an annular recess in the side of the cylindrical member 84, just outside the flange 82. The ring 88, the cylinder 10, and the shaft 52 are all coaxial. The cylindrical member 84 is held from turning by means such as a pin 90 which it carries, and which projects into a radial slot 92 in the plate 14.

In operation, as the shaft 52 is driven, it in turn operates the eccentric 72 to move the cylindrical member 84 with an oscillatory motion, something like a swash plate except that the motion is in its own plane. This member, with the cylinder 10 and the vanes 86, forms a series of expandable and contractible pumping chambers corresponding respectively with the inlet and outlet openings. This forces the fuel from the intake 38 successively through the several connections 30 leading to the different cylinders of the engine.

The quantity of fuel delivered at each revolution can be varied by manipulating the adjustment 78-62 to vary the throw of the eccentric 74.

While one illustrative embodiment has been described in detail, it is not my intention to limit the scope of the invention to that particular embodiment, or otherwise than by the terms of the appended claims.

I claim:

1. A pump and distributor comprising a cylinder, a member mounted therein having slight oscillatory and radial reciprocative movements, a plurality of non-rotating vanes radially mounted thereon, non-yielding means for retaining the vanes against the wall of said cylinder, an eccentric for driving said member, means for driving the eccentric, means for adjusting the eccentric and rendering it ineffective for driving the member operative while the pump is in operation, side walls for the cylinder having the member and the vanes between them, said walls having respectively inlet and outlet openings arranged opposite each other between the vanes, valves controlling said openings, means for delivering fluid to all of said inlet openings, and a separate fluid connection leading from each of the outlet openings.

2. A pump and distributor comprising a cylinder, a member mounted therein having slight oscillatory and radial reciprocative movement, a plurality of non-rotating vanes radially slidably therein, non-yielding means engaging the inner ends of said vanes and holding them against the wall of said cylinder, an eccentric for driving said member, means adjusting the eccentric, while the pump is in operation, side walls for the cylinder having the member and the vanes between them, said walls having respectively inlet and outlet openings arranged opposite each other between the vanes, valves controlling said openings, means for delivering fluid to all of said inlet openings, and a separate fluid connection leading from each of the outlet openings.

3. A pump and distributor comprising a driving shaft having a pair of eccentrics mounted thereon one being shiftable on the other to provide a variable throw while the pump is operating, a cylindrical member driven with oscillatory and radial reciprocative motions in its own plane by the eccentrics, a series of non-rotating radial vanes carried by the cylindrical member and slidably relative thereto as it is driven by the eccentrics, a cylinder encircling and engaged by the outer ends of said vanes, non-yielding means for holding the vanes radially outward against said cylinder, side walls embracing the cylinder between them and forming therewith and with said vanes a series of expandable and contractible pumping chambers, one of said side walls having a valved inlet opening for each of said pumping chambers and one of said side walls having a valved outlet for each of said pumping chambers, means to supply fluid to all of the inlet openings, and a separate fluid connection leading from each of the outlet openings.

cylinder encircling and engaged by the outer ends of said vanes, non-yielding means for holding the vanes radially outward against said cylinder, side walls embracing the cylinder between them and forming therewith and with said vanes and said cylindrical member a series of expandable and contractible pumping chambers, one of said side walls having a valved inlet opening for each of said pumping chambers and one of said side walls having a valved outlet for each of said pumping chambers, means to supply fluid to all of the inlet openings, and a separate fluid connection leading from each of the outlet openings.

4. A pump and distributor comprising a driving eccentric, a cylindrical member driven with oscillatory and radial reciprocative motions in its own plane by the eccentric, a series of non-rotating radial vanes carried by the cylindrical member and slidably relative thereto as it is driven by the eccentric, a cylinder encircling and engaged by the outer ends of said vanes, non-yielding means for holding the vanes radially outward against said cylinder, side walls embracing the cylinder between them and forming therewith and with said vanes and said cylindrical member a series of expandable and contractible pumping chambers, one of said side walls having a valved inlet opening for each of said pumping chambers and one of said side walls having a valved outlet for each of said pumping chambers, means to supply fluid to all of the inlet openings, a separate fluid connection leading from each of the outlet openings and means for varying the throw of the eccentric while the pump is operating.

5. A pump and distributor comprising a driving shaft having a pair of eccentrics mounted thereon one being shiftable on the other to provide a variable throw while the pump is operating, a cylindrical member driven with oscillatory and radial reciprocative motions in its own plane by the eccentrics, a series of non-rotating radial vanes on which the member slides as it is driven by the eccentrics, a cylinder encircling and engaged by the outer ends of said vanes, non-yielding means for holding the vanes radially outward against said cylinder, side walls embracing the cylinder between them and forming therewith and with said vanes and said cylindrical member a series of expandable and contractible pumping chambers, said pump and distributor having a valved inlet opening for each of said pumping chambers and also having a valved outlet for each of said pumping chambers, means to supply fluid to all of the inlet openings, and a separate fluid connection leading from each of the outlet openings.

6. A pump and distributor comprising a driving eccentric, a cylindrical member driven with oscillatory and radially reciprocative movements in its own plane by the eccentric, a series of non-rotating radial vanes carried by the member on which the member slides as it is driven by the eccentric, a cylinder encircling and engaged by the outer ends of said vanes, non-yielding means for holding the vanes radially outward against said cylinder, side walls embracing the cylinder between them and forming therewith and with said vanes and said cylindrical member a series of expandable and contractible pumping chambers, said pump and distributor having a valved inlet opening for each of said pumping chambers and also having a valved outlet for each of said pumping chambers, means to supply fluid to all of the inlet openings,

a separate fluid connection leading from each of the outlet openings, and means for varying the throw of the eccentric while the pump is operating.

7. A pump and distributor comprising a driving eccentric, a cylindrical member driven with oscillatory and radially reciprocative movements in its own plane by the eccentric, a series of non-rotating radial vanes carried by the cylindrical member and on which the cylindrical member slides as it is driven by the eccentric, a cylinder encircling and engaged by the outer ends of said vanes, non-yielding means for holding the vanes radially outward against said cylinder, side walls embracing the cylinder between them and forming therewith and with said vanes and said cylindrical member a series of expandible and contractible pumping chambers, said pump and distributor having a valved inlet opening for each of said pumping chambers and also having a valved outlet for each of said pumping chambers, means to supply fluid to all of the inlet openings, and a separate fluid connection leading from each of the outlet openings, the valves for said openings comprising a pair of plates carrying flappers seating over said openings and moved away from the openings by fluid pressure acting through the

openings, and means for varying the throw of the eccentric while the pump is operating.
